H. H. MORETON

SPOTLIGHT LAMP

Filed March 25, 1921.

Patented Sept. 15, 1925.

UNITED STATES PATENT OFFICE.

HENRY H. MORETON, OF SANTA MONICA, CALIFORNIA, ASSIGNOR TO NATIONAL SPOT LIGHT COMPANY, A CORPORATION OF CALIFORNIA.

SPOTLIGHT LAMP.

Application filed March 25, 1921. Serial No. 455,617.

To all whom it may concern:

Be it known that I, HENRY H. MORETON, a citizen of the United States, residing at Santa Monica, in the county of Los Angeles and State of California, have invented a new and useful Spotlight Lamp, of which the following is a specification.

This invention is a new and useful device for controlling the beam of light projected by a spot light lamp, of the character commonly employed on motor vehicles.

One of the objects of the invention is to provide means for pivotally supporting a spot light lamp, in such manner that its beams may be projected forwardly, to any part of the road in advance of the vehicles to which it is attached, or may be directed laterally, for the convenient reading of sign posts, street numbers and the like. A further object is to provide a simple form of control device in the circuit to the lamp, by means of which the light is automatically turned off while the lamp is being moved through a predetermined portion of the arc of its pivotal movement, with the beam directed straight ahead, thereby preventing said beam from being projected into the eyes of the driver of an approaching vehicle. A further object is to provide a control device of the character mentioned, so constructed that it will be unaffected by movement of the lamp, when the beam is directed laterally of the vehicle. A further object is to provide means whereby the position of the control device may be adjusted, to vary the point in the movement of the lamp, at which the light will be shut off.

The invention will be hereinafter fully set forth and particularly pointed out in the claims.

In the accompanying drawings:

Figure 1 is a top plan view illustrating a spot light lamp constructed in accordance with the invention. Figure 2 is a front elevation. Figure 3 is a cross section on the line 3—3 looking to the left. Figure 4 is a cross section on the line 3—3 Figure 1, looking to the right. Figure 5 is a detail sectional view illustrating the control device.

Referring to the drawings, 10 designates a support clamp, formed of two members having portions shaped to engage any desired part of a motor vehicle, the clamp being illustrated as engaging the frame 11 of the wind shield. The parts of said clamp are retained in clamping position by means of a clamp bolt 12, and nuts 13, in a well-known manner. Gripped between the members of the clamp 10, is one end of a support member 14, said end having flat faces complementary to the inner faces of the clamp members, and having an opening for the passage of the bolt 12. The free end of the support member is provided with a socket 15.

Rotatably mounted in the socket 15 is a carrier member 16 threaded at one end to receive a nut 17, the other end being provided with a split socket 18, arranged on an axis at right angles to the axis of the bore of the socket 15. Rotatably mounted in the socket 18, is one end of a lamp carrier rod 19, the other end of which is provided with a clamp collar 20, which encircles and clamps the spot light lamp 21, which may be of any preferred construction. The portion of the lamp carrier rod 19 which is within the socket 18, is provided with an annular groove 22, which is engaged by the clamp screw 23, for the split socket 18, whereby said rod 19 is free to rotate but is held against withdrawal.

Mounted on the lamp carrier rod 19 is a supporting device 24, which consists of two clamp members *a* and *b*, having portions 25 curved to closely embrace the lamp carrier rod, and having similar portions 26 to receive and clamp switch casing 27. Said members *a* and *b* are held in clamping position by means of a screw 28. By tightening said screw 28, the portions 25 are made to closely embrace the lamp carrier rod 19, and the curved portions 26 will similarly clamp and hold the casing 27.

Located in the switch casing 27 is a switch of any preferred construction. As shown in the drawing, the same consists of a support block 29 of insulating material, provided with a stationary contact 30, and a movable

contact 31. The latter is normally held in engagement with the stationary contact by means of a suitable spring 32. The circuit wires 33 are connected to the respective contacts in a well-known manner. The movable contact is provided with an actuator 34, which projects through the end of the casing 27, in a position to engage a cam 35, formed on the contiguous portion of the support member 14.

In practice the clamp 10 is secured to the windshield frame, or other suitable part of the vehicle, the reflector casing 21 being free to swing horizontally upon the rod 19, and to swing laterally upon the carrier member 16. As the casing 21 swings upon the rod 19 in a direction tending to elevate the beam emanating from the lamp, during any time that the beam is projected forwardly, the actuator 34 will engage the cam 35, and as movement of the casing continues, the circuit to the lamp will be broken by disengagement of the contact members, in a manner which will be obvious from the drawings. During this period the current will be shut off from the lamp and no light will be projected therefrom. Thus as the casing is moved to a point tending to elevate the beam sufficiently high to direct it into the eyes of the driver of an approaching vehicle, the light is shut off and said driver is not subjected to the objectionable glare. However, as pivotal movement of the casing is continued, and it reaches a plane above that of the eyes of the driver of the approaching vehicle, the actuator will have passed the cam 35 and the lamp is again illuminated. At this time, however, the beam is projected at such an angle that it will not interfere with the operation of other vehicles. In other words, there is a certain portion of the arc of movement of the lamp during which the light is entirely shut off. By loosening the clamp screw 28, the switch casing 27 may be rotated to vary the point during the pivotal movement of the lamp, at which the actuator will engage the cam. This adjustment is permitted by reason of the eccentric position of the actuator with respect to the axis of the switch casing. It will thus be seen that by means of the switch and cam, a simple and efficient control device for the circuit to the lamp is provided, the same being adjustable to suit different conditions. When the lamp is swung laterally upon the carrier member 16 as its axis, the actuator 34 is moved away from the cam 35, and the lamp being directed laterally with respect to the vehicle, may be elevated or depressed without the light being affected during any portion of the arc of movement. In a co-pending application Serial No. 413,997, filed October 1, 1920, is described and claimed a device for breaking the circuit to the lamp when the latter reaches a prede-

termined angular position with the beam of light from the lamp projected forwardly. The present case is distinguished therefrom in that the device described and claimed acts only to temporarily break the circuit during a portion of its travel between the two extremes of its normal arc of movement when the beam of light is projected straight ahead. 70

Having thus explained the nature of the invention and described an operative manner of constructing and using the same, although without attempting to set forth all of the forms in which it may be made, or all of the forms of its use, what is claimed is: 75

1. A spot light lamp comprising a lamp carrier rod, means supporting the same in a manner to be supported on axes in approximately the same plane but at right angles to each other, means movable with said rod for temporarily breaking the circuit to the lamp during travel through a portion of its arc of movement on one axis, and a lamp carried by said rod. 80

2. A spot-light lamp comprising a carrier member, means whereby the same is rotatably supported, a lamp, a lamp carrier rod pivotally supported by the carrier member to move on an axis at right angles to the axis of rotation of said carrier member, and means mounted on said lamp carrier rod for temporarily breaking the circuit to the lamp during a portion of its travel between the extremes of its normal arc of movement with respect to the carrier member. 90

3. A spot-light lamp comprising a carrier member, means whereby the same may be rotatably supported, a lamp carrier rod having one end rotatably supported by the carrier member on an axis at right angles to the axis of rotation of the latter, a lamp supported by the other end of said rod and means mounted on said lamp carrier rod for temporarily breaking the circuit to the lamp during travel of the casing through a predetermined portion of its arc of movement with respect to said carrier member while the beam of light is projected forwardly. 100

4. A spot-light lamp of the character described comprising a support member, a carrier member rotatably mounted therein, a lamp carrier rod having means whereby it is rotatably supported by one end of the carrier member on an axis at right angles to the axis of rotation of the latter, a lamp supported by said carrier rod and complementary members, one carried by the support member and the other by the lamp carrier rod for breaking the circuit to the lamp during travel of the casing through a predetermined portion of its arc of movement with respect to said carrier member while the beam of light is projected forwardly. 110

5. A spot-light lamp of the character de- 115

scribed comprising a support member, a carrier member rotatably mounted therein, a lamp carrier rod having means whereby it is rotatably supported by one end of the carrier member on an axis at right angles to the axis of rotation of the latter, a lamp supported by said carrier rod, a cam on said support member, and a circuit controlling device carried by the carrier rod and positioned to engage said cam during the travel of the casing through a predetermined portion of its arc of movement with respect to the carrier member while the beam of light is projected forwardly, said circuit controlling device having means whereby its position may be adjusted with respect to said cam.

6. A spotlight lamp comprising a carrier member, means whereby the same may be rotatably supported, a lamp provided with a rod rotatably supported by one end of the carrier member on an axis at right angles to the axis of rotation of the latter, a supporting clamp secured to said rod, a circuit controlling device mounted in said clamp, and means positioned to temporarily engage the circuit controlling device during travel of the lamp through a predetermined portion of its arc of movement with respect to the carrier member while the beam of light is projected forwardly.

7. A spot light lamp of the character described comprising a support member, a carrier member rotatably mounted therein, a lamp pivotally supported by the carrier member on an axis at right angles to the axis of rotation of said carrier member, a rotatably adjustable circuit controlling device for the lamp having an eccentrically placed actuator, and means positioned to engage said actuator during a portion of the pivotal movement of said lamp.

8. A spot-light lamp comprising a carrier member, means whereby the same may be rotatably supported, a lamp casing having a rod rotatably supported by one end of the carrier member on an axis at right angles to the axis of rotation of the latter, a support bracket shaped at one end to engage said rod, a circuit controlling device mounted in the other end of said bracket, and means positioned to temporarily actuate the circuit controlling device during the travel of the casing through a predetermined arc of its movement with respect to the carrier member while the beam of light is projected forwardly.

9. A spot light lamp of the character described comprising a carrier member, means whereby the same is rotatably supported, a lamp provided with a support rod pivotally mounted in said carrier member on an axis at right angles to the axis of rotation of said carrier member, a support clamp engaging said support rod, a circuit control device mounted in said support clamp, and

means for actuating the circuit controlling device during a portion of the pivotal movement of said lamp.

10. A spot light lamp of the character described comprising a carrier member, means whereby the same is rotatably supported, a lamp provided with a support rod pivotally mounted in said carrier member on an axis at right angles to the axis of rotation of said carrier member, a control device for the circuit to said lamp, separable clamp members engaging said support rod and having portions to receive said control device, a clamp bolt for maintaining said clamp members in clamping position, and means for actuating said control device during a portion of the arc of movement of said lamp.

11. A spot-light lamp of the character described comprising a carrier member having a socket in one end, means whereby the carrier member may be supported to rotate on an axis at right angles to the axis of said socket, a lamp having a support arm rotatably mounted in said socket, a circuit control device mounted upon and movable with said support arm, and means for temporarily actuating said circuit control device during travel of the lamp through a predetermined portion of its arc of movement with respect to the carrier member while the beam of light is projected forwardly.

12. A spot-light of the character described comprising a support member having a socket, a carrier member rotatably mounted in said socket, a lamp casing having means whereby it is rotatably supported by the carrier member on an axis at right angles to the axis of rotation of the latter, a circuit control device movable with the lamp casing, and means on the socket of said support member positioned to temporarily engage the circuit closing device during travel of the lamp casing through a predetermined portion of its arc of movement with respect to the carrier member while the beam of light is projected forwardly.

13. A spot-light lamp of the character described comprising a support member having a socket, a carrier member rotatably mounted in the socket, a lamp casing pivotally supported by the carrier member on an axis at right angles to the axis of rotation of said carrier member, and a circuit control device movable with the lamp casing, said socket having a peripheral enlargement positioned to temporarily engage the circuit control device during the travel of the casing through a predetermined portion of its arc of movement with respect to the carrier member while the beam of light is projected forwardly.

14. A spot-light lamp of the character described comprising a support member having a socket provided with a cam, a carrier member rotatably mounted in said socket, a

lamp casing pivotally supported by the carrier member on an axis at right angles to the axis of rotation of the latter, a circuit control device, means for adjustably securing said device to move with the lamp casing, said device being normally positioned to temporarily engage said cam during travel

of the lamp casing through a predetermined portion of its arc of movement with respect to the carrier member while the beam of light is projected forwardly.

In testimony whereof I have hereunto set my hand.

HENRY H. MORETON.
